BUTT-WELDING APPARATUS

Oren B. Harmes, Algona, Iowa, assignor of one-half to
Ladish Co., Tri-Clover Division, Kenosha, Wis., a cor-
poration of Wisconsin

Filed Feb. 8, 1960, Ser. No. 59,297

Term of patent 14 years

(Cl. D26—1)

FIG. 3

FIG. 4

FIG. 5

FIG. 6

Fig. 1 is a front perspective view of a butt-welding apparatus showing my new design;

Fig. 2 is a side perspective view;

Fig. 3 is an opposite side elevational view;

Fig. 4 is a rear elevational view thereof;

Fig. 5 is a fragmentary front elevational view on an enlarged scale of the welder portion of my apparatus; and

Fig. 6 is a fragmentary side elevational view on an enlarged scale of the welder portion thereof.

A portion of the wire is shown in broken lines for convenience in illustration.

I claim:

The ornamental design for a butt-welding apparatus, as shown and described.
